UNITED STATES PATENT OFFICE.

THOMAS W. POWER, OF WASHINGTON, DISTRICT OF COLUMBIA.

NON-FURLING DEVICE FOR BANNERS.

1,311,712.

Specification of Letters Patent. Patented July 29, 1919.

Application filed June 12, 1919. Serial No. 303,547.

To all whom it may concern:

Be it known that I, THOMAS W. POWER, a citizen of the United States, and a resident of Washington, District of Columbia, have 5 invented certain new and useful Improvements in Non-Furling Devices for Banners, of which the following is a specification.

This invention relates to a device for preventing banners, or flags, from becoming 10 furled or wrapped about their poles when displayed in the wind.

One object of the invention is to provide a simple and inexpensive device for accomplishing the desired purpose and which 15 may be easily but firmly attached to a flag without danger of tearing or otherwise injuring the same.

Another object is to provide means for firmly attaching the device to the flag pole 20 without interfering with the engagement of the latter with its holder or diminishing the supporting strength of the pole.

The invention also contemplates the provision of an automatically adjustable weight 25 adapted to be regulated to accord with the size of the flag, and which will yield to permit said flag to wave gracefully in the breeze but bring it back to smooth depending position when the breeze dies down.

30 Other objects will appear as the description proceeds.

The invention will be first hereinafter described in connection with the accompanying drawings, which constitute part of this 35 specification, and then more specifically defined in the claims at the end of the description.

In the accompanying drawings, wherein 40 similar reference characters are used to designate corresponding parts in each of the several views—

Figure 1 is a side elevation of a flag mounted on its pole, supported from a window sill, and equipped with a non-furling 45 device made and applied substantially in accordance with this invention.

Fig. 2 is a similar view, showing the operation of the device when the flag waves in the breeze.

50 Figs. 3 and 4 are detailed edge and side views of the clamp to be attached to the flag.

Figs. 5 and 6 are similar views of the clamp to be attached to the pole.

Figs. 7 and 8 are similar views of the automatically adjustable trolley hanger and 55 weight which are suspended from the flexible connection or rope extending between the flag and pole clamps, as shown in Figs. 1 and 2; and

Fig. 9 is an edge view of a trolley hanger 60 and weight designed for use with a larger flag.

In Figs. 1 and 2, part of a window frame is illustrated at 10, and a common form of flag pole holder 11 is shown attached to the 65 window sill 12. The flag pole 13 may be supported by said holder at any desired angle, the position illustrated being substantially that generally observed. The non-furling device consists of a clamp 14 70 to be secured to the free end of the flag 15, a clamp 16 to be secured to the pole 13, a flexible connection or rope 17 to extend loosely between said clamps, substantially as shown, and a trolley supported weight 75 18, mounted on said flexible connection so as to run along the same for permitting the flag to wave gracefully in the breeze as indicated in Fig. 2, and for automatically bringing the flag back to smoothly depending position when the breeze goes down; the weight being heavy enough to prevent the flag from furling without interfering with its waving.

The clamp 14 comprises a pair of plates 85 19 and 20 having supplemental corrugated abutting faces 21, as shown in Fig. 3. These plates may be made of any desired material, preferably sheet metal, aluminum or the like. The plates are clamped together, so as to grip a portion of the free end of the flag between them, being held together by bolts 22. Each plate has a semi-tubular projecting portion 23 and 24, respectively, which together form a tube 25 95 when the plates are clamped together. The ends of said tube are preferably flared, as at 26, to facilitate the threading of the rope 17 through the same.

The clamp 16 comprises a pair of supplemental straps 27 and 28, which together 100 form a collar 29, adapted to be clamped around the flag pole near the holder 11, by bolts 30.

These straps also have supplemental semi-tubular portions 31 and 32, respectively,

which form a tube 33 when the straps are connected together as best shown in Fig. 5. The ends of the tube 33 are also preferably flared, as at 34, to facilitate the threading 5 of the rope through it.

By reason of the construction of the tubes 25 and 33, with the flared ends 26 and 34, respectively, the ends of the rope 17 may be easily passed through them in either direction, and connected to the clamps 14 and 16, by simply tying knots in the extremities of the rope, as shown at 35 in Figs. 1 and 2.

In order that the rope may not interfere with the waving of the flag, it is loosely hung between the clamps, and to prevent the flag from wrapping around the pole with the rope, the weight 18 is suspended by a hanger 36, having a sheave 37 to run on said rope. The weight is detachably connected 20 to the hanger by means of a bolt 38, permitting weights of different sizes to be substituted for one another to suit flags of different sizes. In lieu of changing the weights, however, one or more additional weights, 39, 25 may be attached to the initial weight 18, in any suitable manner, as by bolts 40 passed through holes 41 in said weights. It will thus be seen that by varying the size of the weights, flags of different sizes may be 30 nicely counterbalanced and adjusted to permit the desired waving but avoid the objectionable furling thereof.

Having thus fully described my invention, what I claim as new and desire to secure by 35 Letters Patent of the United States, is—

1. A non-furling device for banners comprising a flexible connection loosely suspended between the free end portion of the banner and a fixture.
- 40 2. A non-furling device for banners comprising a flexible connection extending between the free end portion of the banner and a fixture, and a weight on said flexible connection.
- 45 3. A non-furling device for banners comprising a flexible connection extending loosely between the free end portion of the banner and a fixture, and a weight mounted to automatically travel along said flexible connection.

4. A non-furling device for banners, comprising a loosely suspended flexible connection, a clamp for gripping the free end portion of the banner and having means for 55 securing one end portion of said flexible connection thereto, and means for attaching the other end portion of said flexible connection to a fixture.

5. A non-furling device for banners comprising a loosely suspended flexible connection, a clamp for gripping the free end portion of the banner, a tubular member carried by said clamp, and through which one end portion of the flexible connection may be

threaded for attachment thereto, and means 65 for attaching the other end portion of said flexible connection to a fixture.

6. A non-furling device for banners comprising a loosely suspended flexible connection, a clamp consisting of a pair of supplemental corrugated plates to grip the free end portion of the banner between them, means for securing one end portion of the flexible connection to said clamp and means for securing the other end portion of said 75 flexible connection to a fixture.

7. A non-furling device for banners comprising a loosely suspended flexible connection, a clamp consisting of supplemental plates adapted to grip the free end portion 80 of the banner between them, said plates having semi-tubular projections to form a tube for attaching one end portion of the flexible connection to the clamp when the plates are secured together, and means for securing the 85 other end portion of said flexible connection to a fixture.

8. A non-furling device for banners comprising a loosely suspended flexible connection, a clamp consisting of supplemental 90 plates adapted to grip the free end portion of the banner between them, said plates having semi-tubular projections to form a tube for attaching one end portion of the flexible connection to the clamp when the plates are 95 secured together, the ends of said tube being flared for the purpose specified, and means for securing the other end portion of said flexible connection to a fixture.

9. A non-furling device for banners comprising a loosely suspended flexible connection, a clamp consisting of supplemental members to grip a fixture, said members having supplemental semi-tubular projections to form a tube for attaching one end 105 portion of the flexible connection thereto when the members are secured together, and means for securing the other end portion of said flexible connection to the banner.

10. The combination with a banner and a 110 pole for supporting the same, of clamps for gripping said pole and the free end portion of said banner, and a loosely suspended flexible connection extending between said clamps.

11. A non-furling device for banners comprising a flexible connection extending loosely between the free end portion of the banner and a fixture, a weight mounted to automatically travel along said flexible connection, and means for varying the size of 120 said weight for the purpose specified.

12. A non-furling device for banners comprising a flexible connection to extend loosely between the free end portion of said 125 banner and a fixture, a trolley hanger to run on said flexible connection, and a weight detachably secured to said hanger.

13. A non-furling device for banners comprising a flexible connection to extend loosely between the free end portion of said banner and a fixture, a weight suspended from said flexible connection, and means for securing additional weights to the initial weight.

14. A non-furling device for banners comprising a flexible connection to extend loosely between the free end portion of said banner and a fixture, a trolley hanger to run on said flexible connection, and a weight secured to said hanger. 10

THOMAS W. POWER.
